Primary Examiner — David G Muller*(74) Attorney, Agent, or Firm* — Dragon Sun Law Firm, PC; Jinggao Li, Esq.(57) CLAIM

The ornamental design for a colostrum collector, as shown and described.

DESCRIPTION

FIG. 1 is a perspective view of a colostrum collector showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown in the figures depict portions of the colostrum collector that form no part of the claimed design.
